- FIG - 4 -

INVENTOR.

BY Z. V. MORVAY,
Elwood H. Seal,
ATTORNEY.

UNITED STATES PATENT OFFICE.

ZOLTAN V. MORVAY, OF BRIDGETON, NEW JERSEY.

DUPLEX FOLDER.

Application filed September 16, 1926. Serial No. 135,757.

My invention, in its broad aspect, has reference to improvements in attachments for sewing machines, especially of the double needle variety, whereby elastic webbing or tape, or for that matter ribbon, binding, facing, tape, or the like, may be sewn into textile material without the utilization of a separate strip of material or facing strip. Material so provided with elastic inserts are common in the manufacture of bloomers, rompers, drawers, garters, and the like, but so far as I am aware, my present invention is unique in accomplishing this result by means of an S-shaped fold in the material in one of the loops of which the elastic is trained and said loop sewn down to form the tube for retaining the elastic, and reinforcing the portions of the material adjacent the same. To this end I have provided novel mechanism which may be set up in conjunction with a conventional form of sewing machine to the end that the operations of tucking, sewing, and placing the elastic member will be accomplished mechanically and with facility.

In addition to the above, other and equally important advantages of my invention may be briefly defined as follows; first, I provide a pair of tuck forming members or plates, one of which is S-shaped, and has formed therein by one of the loops of the S-shaped configuration a tube which holds and trains the elastic member, thereby simplifying the structure; second, all parts of my device are positive in operation; third, binding of any of the parts is prevented; fourth, the apparatus may be attached to an ordinary sewing machine without materially altering any of its parts; fifth, there are no fragile or concealed parts which might easily get out of order, and any of the parts may be readily replaced or cleaned, and; sixth, the assembly is capable of being manufactured at relatively small cost and sold at a reasonable retail price.

To these and other ends, my apparatus consists in the construction, arrangement and combination of parts described hereinafter, illustrated in the drawings, and defined in the claims forming a part of this specification.

One embodiment of my invention is represented by way of example in the accompanying drawings, wherein;

Figure 1 is a substantially diagrammatic

view of a sewing machine, shown in perspective, and having my attachment mounted thereon;

Figure 2 is a reduced detail view of a portion of the mechanism, and

Figure 3 is an enlarged perspective view showing the principal parts of my invention in their relative working positions.

Figure 4 is a diagrammatic perspective view showing the several parts of my device in detail, and in their working relationship to each other.

In the drawings wherein like characters of reference are used to designate like or similar parts throughout the several views;—

(1) designates a sewing machine of the double needle variety and having a foot (2), spools (3), and a work support (4) beneath which is the bobbin structure (not shown). Mounted beneath the machine is a spool of elastic material or tape (5) which is fed through an opening (6) to the work support where it is received by my machine in the manner which will be hereinafter described.

My invention contemplates the provision of two plates (7) and (8), the lower most plate (8) being S-shaped and having an extension (9) adjustably secured as at (10) to a guide rod (11) which is pivotally engaged as at (12) by the link connection to the crank (13), the other arm of which is fixed to a shaft (14). The shaft (14) is journaled through a bracket (15) mounted upon the work table or support (4) of the sewing machine and which has two upright, spaced arms (16) forming the shaft journalling and supporting members. The shaft has fixed thereon an arm (17), and at its end another arm (18). A spring (19) normally urges the shaft to position the arms (17) and (18) as in Figure 2.

Pivoted to the arm (17) is a link (20) which is connected at its opposite end with a foot or lever arm (21) pivotally attached to a bracket (22) carried by the sewing machine (1). The foot or lever arm (21) is curved downwardly at its free terminal and has thereon a nickeled steel cap (23). The arm (18) is connected by a link (24) to a transverse rod (25)—shown in dotted lines—journaled beneath the work support or table (4), and attached thereto is a knee-presser member (26), so that when said member (26)

is pressed by the operator, the motion is transmitted to the foot or lever arm (21) to cause the cap end (23) to move forward. Interposed in the path of movement of the lever 5 arm or foot (21) is a rod (27) having a head or cap (28) for contact with the foot (23). The rod (27) is journalled through an adjustable clamp (29) through which extends the presser footbar (30)—shown in dotted lines in 10 Figure 3—and a brass bearing member (31) fits about the rod (27) to properly journal the same. A spring (32) is of the double acting variety and holds the rod normally in a retracted position and has its ends attached to 15 the clamp (29) and cap (28) so that the rod (27) is normally urged to its upper position as shown in Figure 1 from which it is forced outwardly from time to time by the bell-hanger or foot (21) when the operator 20 presses the knee-presser member (26). The rod (27) is bent intermediate its length as at (33) and is attached to plate (7) of my mechanism which same is bent to conform substantially to the shape of one of the loops in 25 plate (8). Thus, when knee presser member (26) is pressed the rod (27) is forced forward to ride over the end of the guide or stop trip (24), consequently when the knee presser member is released the expansion action of 30 the spring (32) causes it to ride down beneath the trip (34) to engage the folder plates to form the tuck. The spring (32) is normally wound up, after the manner of a watch spring, so that the latter action is against the action 35 of the spring in unwinding it but with the action of the spring in the exertion of its expansion force. Stop pins (35) are mounted on the rod (27) to prevent it from binding or jamming. In Figure 1 the plate (7) is swung 40 up from the work table or support, but the spring (32) normally holds it in the position shown in Figure 1.

The material (36) is fed into the machine and the plates (7) and (8) are moved toward 45 each other to tuck the material as shown at (37) and (37') the elastic tape (38) is carried in the tube portion (39) formed by the S-shaped conformation of the plate (8), and is fed into tuck (37) whereupon the tucks 50 (37) and (37') are stitched down as at (40) forming a reinforced tube for the elastic member. The material is also tucked in the usual manner at intervals transversely of the elastic member by the presser foot of the 55 machine and the natural retractile properties of the elastic. The elastic member is carried from the opening (6), from spool (5), through guide slots (41) and (41') in extension (9) of plate (8) to the tube portion (39) 60 thereof so that binding and the like is prevented. When the tuck has been stitched down the knee member is again pressed which moves the tucking plates 7 and 8 apart and causes rod 33 to ride up on the trip member 65 (34) to assume again the position shown in

Figure 1. The upward movement of the rod is caused by the expansion force of the spring (32). The operation of my device can be readily understood by reference to Figure 4 which is a diagrammatic view of my invention showing the relationship of the parts during the cycle of operation. In the full line position, the parts are shown in a neutral position or with the plates (7) and (8) in position to form the tuck. The knee 70 presser member (26) is released or down and the spring (32) expanded. Suppose now that it is desired to form a tuck in a new piece of stock; the knee presser member (26) is moved to the right, drawing down the rod (24) and link (18); this turns the shaft (14) against the force of spring (19) and moves the arm (17) back, thus drawing the rod (20) to tilt up the member (21), as shown in dotted lines. The capped end (23) of member (21) 75 then presses on head (28) to cause rod (27) carrying plate (7) to move out. However, the spring (32) is of the double acting variety and is normally wound up, after the manner of a watch spring, thus the plate will be urged 80 up along the guide (34) by the spring to take the position shown in dotted lines (or in full lines in Figure 1). The stock is then inserted and the knee presser member released, whereupon spring (19) will cause the knee-presser 85 member to move to the left, and the remaining elements in conjunction therewith will again be moved to the full line position including the rod (20) and member (21). The head 90 (28) will be forced out by pressure of spring (32) drawing the rod (27) down along the guide or trip (34), and disposing the plate (7) in the full line position to tuck the stock. The stock is now ready to be stitched along 95 the tuck with the elastic material in place. Attention is again directed to the fact that by my machine elastic material or tape may be incorporated into the stock simply by forming an S-shaped tuck therein, whereas heretofore it has been customary to secure the 100 elastic in place by a separate facing strip. 105

To these and other ends, my machine consists in the construction defined in the appended claims, but it is desired to emphasize the fact that interpretation of the invention 110 should only be conclusive when made in the light of the language of such claims. 115

I claim:—

1. An attachment for sewing machines comprising a pair of plates, means for actuating said plates toward and away from each other, one plate having an S-shaped cross-sectional curvature for cooperation with the other plate to form a tuck in material passed between the plates, and said S-shaped plate having a tube formed by one of its bends to receive and guide a tape element to position in the tuck for the purpose defined. 120

2. An attachment for sewing machines comprising a pair of plates, means for actu- 125

ating said plates toward and away from each other, one plate having an S-shaped cross-sectional configuration throughout its length, the other plate being curved to simulate the curvature of a portion of the other plate and adapted to cooperate therewith to form a tuck in material passed between the plates,

and said S-shaped plate having a tube formed by one of its bends to receive and guide a tape element to position in the tuck for the purpose defined. ¹⁰

In testimony whereof, I affix my signature hereunto.

ZOLTAN V. MORVAY.
